REVERSIBLE PICTURE FRAME AND MIRROR

William H. Stefanakis, Long Beach, N. Y.

Application July 30, 1956, Serial No. 42,450

Term of patent 14 years

(Cl. D29—20)

Figure 1 is a front perspective view of a reversible picture frame and mirror, embodying my new design;

Figure 2 is a side elevational view; and

Figure 3 is a reduced rear perspective view thereof.

I claim:

The ornamental design for a reversible picture frame and mirror, as shown.
